UNITED STATES PATENT OFFICE.

CHARLIE C. INMAN, OF ROACHDALE, INDIANA, ASSIGNOR OF ONE-HALF TO
JOHN H. GRANTHAM, JR., OF ROACHDALE, INDIANA.

VENDING-MACHINE.

No. 853,977.

Specification of Letters Patent.

Patented May 21, 1907.

Application filed May 31, 1906. Serial No. 319,450.

To all whom it may concern:

Be it known that I, CHARLIE C. INMAN, a citizen of the United States, residing at Roachdale, in the county of Putnam and State of Indiana, have invented certain new and useful Improvements in Vending-Machines, of which the following is a specification.

The object of my invention is to produce an apparatus by means of which articles, such as cigars, may be automatically vended, the operability being dependent upon coin controlled mechanism.

The accompanying drawings illustrate my invention:

Figure 1 is a perspective view of an apparatus embodying my invention; Fig. 2, a sectional rear elevation; Fig. 3, a vertical section of the selecting mechanism on an enlarged scale; Fig. 4, a horizontal section on line 4—4 of Fig. 3; Fig. 5, a section on line 5—5 of Fig. 3; Fig. 6, a longitudinal sectional detail of the removing mechanism; Fig. 7, a horizontal section of a portion thereof; Fig. 8, an end elevation of the gripping jaws; Fig. 9, a section on line 9—9 of Fig. 4; Fig. 10, a perspective detail of a portion of the wheel locking mechanism.

In the drawings 10 indicates a wheel suitably journaled in an inclosing casing 11, adapted to be driven by a small electric motor 12. Wheel 10 carries an annular plate 13 supporting a cylindrical body 14 having a plurality of pairs of arms 15 between each pair of which is pivotally mounted a cradle 16 adapted to receive boxes 17 of merchandise such as cigars 18, said boxes being conveniently held in their cradles by means of clips 19 held against the boxes by a spring 20.

The plate 13 is provided with a plurality of holes 21, one for each cradle 16, and these holes are arranged at varying distances from the center of the wheel 10 to register with one or the other of a series of spring plungers 22 which are reciprocably mounted in a frame 23 and each is normally held retracted against the action of its spring 24 by means of a finger 25 (one for each plunger), through which the ensmalled ends 22' of the plungers 22 are passed, a nut 22" being placed upon the outer end of each ensmalled portion and said ensmalled portions being of a length considerably greater than the thickness of the fingers

25 so that there may be a relative movement equal to the full stroke of the fingers 25.

Each finger 25 carries a push-pin 26 which projects from the casing 11 and is provided at its outer end with a suitable finger head 26'. The several fingers 25 engage a bar 30 which, at one end, engages with a cam shaped portion 31' of a latch 31 yieldingly urged in one direction by a spring 32. The bar 30 carries a plunger 33 which registers with an opening 34' formed in a frame 34 reciprocally mounted on the frame 23 and said plunger normally urged in one direction by a spring 35. Leading to the space immediately in front of the perforation 34', and between that portion of the frame 34 containing said perforation and the inner end of plunger 33, is a coin chute 40 the outer end of which opens to the exterior of casing 11 the arrangement being such that, until coin 41 is introduced between the inner end of plunger 33 and the adjacent portion of frame 34 the plunger may be reciprocated freely without shifting said frame.

The frame 34 carries a projection 341 adapted to be engaged by the latch 31 when the frame has been projected by plunger 33 with a coin properly placed, and when in this position a portion 342, carried by frame 34, makes electrical contact with a terminal 343 thus closing the circuit C of the motor 12 and holding it closed so long as latch 31 lies behind the projection 341. The plate 13 is provided with a series of holes 50 one for each of the cradles 16 which holes are adapted to receive the two plungers 51 and 52 preferably formed by two half-round members placed together and slidably mounted in brackets 53 carried by the frame 23. Plunger 51 may be reciprocated by means of a lever 54, and plunger 52 may be reciprocated by a lever 55. The lever 54 is connected by link 56 with bar 30, while lever 55 is extended so as to lie in the path of movement of a portion 344 of frame 34. Each plunger 51 and 52 is yieldingly urged toward locking position by a spring 57.

The cigars may be singly engaged by means of a pair of grasping jaws 60 and 61, the jaw 60 being carried by the inner end of a tube 62 while the jaw 61 is pivoted to the jaw 60, a spring 63 normally holding said jaws separated. Attached to jaw 61 is a wire 64 which passes through the tube 62 and is at-

tached at its outer end to a handle 65 by means of which it may be pulled so as to bring the jaw 61 toward the jaw 60. The tube 62 is mounted in a head 66 which is pivoted on a horizontal axis 67 in the casing 11, the tube 62 being longitudinally reciprocal through the head 66. The opening 68 in the said head 66 through which the tube 62 passes is widened at its inner end as shown in Fig. 7 to permit a swinging of the tube 62 in an axial plane. Head 66 carries an arm 69 to the inner end of which is pivotally attached a depending locking bar 70 which, at its lower end, passes through an opening 71 formed through a portion 231 of the frame 23. The lock bar 70 is provided near its lower end with a shoulder 72 which is adapted to normally lie above the portion 231 of the frame 23, the lock bar being yieldingly urged to this position by a spring 73, the arrangement of the lock bar being such that, when it is in the position shown in Fig. 3, there can be no swinging of the head 66 on its pivotal axis 67 and the grasping jaws 60 and 61 cannot, therefore, be lowered into any one of the receptacles 17. Pivoted upon the frame 34 is a spring pawl 76 adapted to engage the lower end of lock bar 70 when the frame 34 returns to its normal position.

30 The operation is as follows: With the parts in the position shown in Figs. 3 and 4, a coin of the proper denomination has been inserted into the coin passage 40 and has passed from thence to the proper position between the frame 34 and the inner end of plunger 33. Thereupon the operator will press inward upon the particular finger button 26' which is indicated as belonging to the particular cigar which he desires to purchase. This movement will push plunger 33 inward against the coin 41 and thus shift frame 34, to the right in Fig. 4, to the position indicated by dotted lines in said figure thus completing the motor circuit so that it will begin to rotate the wheel 10. This movement of the frame 34 carries pawl 76 past the lower end of the lock bar 70 and said pawl yields in this direction and the latch 31 drops behind portion 341 so as to hold the frame 34 in the new position. At the same time the particular finger 25 carried by the operated push pin 26 releases the corresponding plunger 22 and permits it to be urged by its spring 24 into engagement with the disk 13. The movement of bar 30 also, through link 56, swings lever 54 so as to withdraw the locking plunger 51 from plate 13 and the movement of frame 34 swings lever 55 so as to withdraw the locking plunger 52 from plate 13. As soon as the two plungers 51 and 52 are withdrawn from plate 13 the motor will rotate wheel 10 together with all the parts carried thereby until the proper hole 21, which is placed to register with the operated plunger 22, comes opposite said plunger whereupon

said plunger enters said hole and stops the rotation of the wheel. As soon as this occurs the operator releases the pressure upon the selected push pin 26 thus permitting the coin to drop into the coin trough 80 (shown in dotted lines in Fig. 4), and the bar 30 to return to normal position said bar engaging the cam portion 31 of latch 30 so as to withdraw said latch from behind said portion 341 and thus permit frame 34 to be returned by its spring 35 to normal position. As the frame 34 returns to normal position the pawl 76 engages the lower end of the lock bar 70 and withdraws its shoulder 72 from engagement with portion 231 and permits said lock bar to drop down through opening 71 thus permitting the jaws 60 and 61 to drop down into the uppermost box 17. As soon as pressure is released on the operated push pin, plunger 51 is returned into engagement with disk 13 and enters one of the holes 50 thus holding the wheel from further rotation, and when the frame 34 returns to its normal position the plunger 52 is also projected into the same hole 50. The operator is now free to manipulate the jaws 60 and 61 by a manipulation of the tube 62 and handle 65 so as to grasp a single cigar. As soon as this is done the operator will project the jaw head upward and inward until it lies over the discharge trough 81, but this position cannot be reached except by swinging the head 66 on its pivot 67 until shoulder 72 is brought above portion 231 of frame 23 and spring 73 returns the lock bar 70 to its normal position so as to prevent a return of the jaw head for another load. The cigar which has been selected may be released by a separation of the jaw 61 from jaw 60 and it will slide down the trough 81 to the exterior of the casing.

It is not absolutely essential to have the double locking plunger 51—52, as the plunger 52 may be omitted if desired, but in such case it will be seen that the plunger 51 may be withdrawn from the plate 13 by a manipulation of any one of push pins 26. This will not permit the operation of any of the other mechanism, nor the selection of a cigar, neither will it complete the circuit of the motor and consequently there will be no rotation of the wheel unless it should happen that it was unbalanced, in which case there will be a movement to a balanced position. I deem it advisable, therefore, to provide the additional locking plunger 52 to prevent such action.

I claim as my invention:

1. In a coin controlled vending machine, the combination with a containing casing, and a rotatable carrier provided with a plurality of receptacles, of a motor for rotating said carrier, selecting mechanism for stopping said carrier to present any one of the receptacles in delivering position, coin-controlled mechanism, grasping means arranged with

the casing, means dependent upon the coin controlled mechanism for locking said grasping means, accessible means for manipulating said grasping means from the exterior of 5 the casing, and means controlled by the coin controlling means for connecting and disconnecting the motor and for releasing said locking means.

2. In a coin controlled vending machine, 10 the combination with a containing casing, of a carrier provided with a plurality of receptacles, of a motor for driving said carrier, selecting mechanism for stopping said carrier to present any one of the receptacles in 15 delivering position, coin-controlled mechanism, grasping means arranged with the casing, means dependent upon the coin controlled mechanism for locking said grasping means, accessible means for manipulating said 20 grasping means from the exterior of the casing, and means controlled by the coin controlling means for connecting and disconnecting the motor and for releasing said locking means.

25 3. In a coin controlled vending machine, the combination with an inclosing casing, a rotatable carrier mounted therein and provided with a plurality of containers, means for rotating said carrier, and a coin controlled 30 means for controlling the movement of said carrier and stopping the same at any desired position, of ejecting means comprising a member accessible at one end from the exterior of the casing and provided at its inner 35 end with means for engaging an article, a supporting head for said member pivoted in the casing, a locking bar for said head and means controlled by the selecting means for operating said locking bar.

40 4. In a coin controlled vending machine, the combination with an inclosing casing, a rotatable carrier mounted therein and provided with a plurality of containers, means for rotating said carrier, and a coin controlled 45 means for controlling the movement of said carrier and stopping the same at any desired position, of a head pivoted in said casing, a locking bar carried by said head and adapted to normally restrain pivotal movement of 50 said head, means controlled by the selecting mechanism for releasing said locking bar, an ejector member carried by said head and movable therein, said ejector member accessible from the exterior of the casing at one end 55 and carried at its other end, and means for engaging an article carried by the carrier.

5. In a coin controlled vending machine, the combination with an inclosing casing, a rotatable carrier mounted therein and provided with a plurality of containers, means for rotating said carrier, and a coin controlled 60 means for controlling the movement of said carrier and stopping the same at any desired position, of a head pivoted in said casing, a locking bar carried by said head and adapted 65

to normally restrain pivotal movement of said head, means controlled by the selecting mechanism for releasing said locking bar, an ejector member carried by said head and longitudinally movable therethrough, a pair of 70 grasping jaws carried by the inner end of said member, and means at the accessible outer end of said member for the manipulation of said jaw.

6. In a coin controlled vending machine, 75 the combination with inclosing casing, a rotatable carrier mounted therein and provided with a plurality of containers, means for rotating said carrier, a coin controlled means for controlling the movement of said 80 carrier and stopping the same at any desired position, of a head pivoted in said casing, a locking bar carried by said head and adapted to normally restrain pivotal movement of said head, means controlled by the selecting 85 mechanism for releasing said locking bar, and ejector member carried by said head and transversely movable therethrough, a pair of grasping jaws carried by the inner end of said member, and means at the accessible outer 90 end of said member for the manipulation of said jaws.

7. In a coin controlled vending machine, the combination with an inclosing casing, of a rotatable carrier mounted therein and provided with a plurality of containers, a motor for rotating said carrier, a plurality of accessible members and a corresponding plurality of locking pins adapted to engage the carrier at predetermined positions, a coin controlled 100 member which may be actuated by any one of the accessible members, means controlled by said member for actuating the motor, and a locking member normally engaging the carrier and operable by any one of the accessible 105 members.

8. In a coin controlled vending machine, the combination with an inclosing casing, of a rotatable carrier mounted therein and provided with a plurality of containers, a motor 110 for rotating said carrier, a plurality of accessible members and a corresponding plurality of locking pins adapted to engage the carrier at predetermined positions, a coin controlled member which may be actuated 115 by any one of the accessible members, means controlled by said member for actuating the motor, and a pair of locking members operable by any one of the accessible members and the other of said locking members operable by the coin controlled members. 120

9. In a coin controlled vending machine, the combination with an inclosing casing, of a rotatable carrier mounted therein and provided with a plurality of containers, a motor 125 for rotating said carrier, a plurality of accessible members and a corresponding plurality of locking pins adapted to engage the carrier at predetermined positions, a coin controlled member which may be actuated 130

by any one of the accessible members, means controlled by said member for actuating the motor, a locking member normally engaging the carrier and operable by any one of the accessible members, an ejector member movably mounted in a pivoted head, a locking member for normally holding said head against movement permitting engagement of the ejector member with the articles to be vended, and means controlled by the coin controlled member for releasing said locking member.

10. In a coin controlled vending machine, the combination with an inclosing casing, of a rotatable carrier mounted therein and provided with a plurality of containers, a motor for rotating said carrier, a plurality of accessible members and a corresponding plurality of locking pins adapted to engage the carrier at predetermined positions, a coin controlled member which may be actuated by any one of the accessible members, means

controlled by said member for actuating the motor, a pair of locking members normally engaging said carrier one of said locking members operable by any one of the accessible members and the other of said locking members operable by the coin controlled members, an ejector member movably mounted in a pivoted head, a locking member for normally holding said head against movement permitting engagement of the ejector member with the articles to be vended, and means controlled by the coin controlled member for releasing said locking member.

In witness whereof, I, have hereunto set my hand and seal at Indianapolis, Indiana, this 23d day of May, A. D. one thousand nine hundred and six.

CHARLIE C. INMAN. [L. s.]
